UNITED STATES PATENT OFFICE.

GEORGE B. SPARKS, OF WOODBURY, NEW JERSEY.

VENTILATED HELMET.

1,113,062.

Specification of Letters Patent.

Patented Oct. 6, 1914.

Application filed December 27, 1912. Serial No. 738,947.

To all whom it may concern:

Be it known that I, GEORGE B. SPARKS, a citizen of the United States, residing at Woodbury, in the county of Gloucester and 5 State of New Jersey, have invented a certain new and useful Ventilated Helmet, of which the following is a specification.

This invention relates to helmets for workmen employed in confined spaces containing 10 impure air, gases, or dust, which are injurious to breathe, and it has for its object to provide a simple, comparatively inexpensive, and durable apparatus adapted to be readily applied to the person and to supply fresh air in a constant stream, or as it may be needed, and to deliver the same without inconvenience to the wearer, and it consists of the parts and combinations of parts hereinafter described and claimed.

20 In the accompanying drawings forming a part of this specification Figure 1 is a front elevation of my improved helmet. Fig. 2 is a vertical section on the line 2—2. Fig. 1. Fig. 3 is a detail plan view of the head piece. 25 Fig. 4 is a horizontal section on the line 4—4. Fig. 1. Fig. 5 is a detail front elevation of the head piece.

Similar letters refer to similar parts throughout all the views.

30 Referring to the drawings A represents the helmet, proper, which consists of a thin shell roughly resembling, and of a size to fit over the human head to leave ample space at all points about the same. In the shell 35 an opening is formed at one side thereof which extends from the base or bottom of the shell sufficiently high and wide to readily admit the wearer's head. The opening is closed by a door B which is hinged to the 40 shell and carries a latch a for engagement with a notch b. The door B is filled with glass c which is secured air-tight in place, as by a gasket d around its edges. Within the shell is secured a head piece which rests 45 on the head of the wearer when the helmet is in place. The head piece consists of a metal band C having a lining D of some suitable soft material, such as leather, to prevent chafing, the ends of said band being free and 50 overlapped and one end carrying a hook e adapted to enter perforations f formed in the other end. The band is connected by curved metal strips E, extending longitudinally and transversely, which rest on the 55 head of the wearer, and the whole is sup-

ported in the shell by a suitable number of spiral springs g attached at one end to the band and at the other to the shell. The head piece may be adjusted to fit the head by drawing the ends of the band past each other and securing the same in their adjusted position by catching the hook e in one of the perforations f.

From the above description it will be understood that the attachment of the head-piece to the shell, by means of springs permits of a free movement of the head within the helmet and also gives greater ease and comfort to the wearer since the helmet shell is supported away from the head and any 60 blows or shocks received by the latter are not transmitted to the head.

At one side of the shell near the doorway a pipe F enters the helmet and the point of entrance thereof is made air-tight in any 65 preferred manner. The pipe curves around or follows the contour of the shell from its entrance to a point near the opposite side of the doorway. A series of perforations h are formed in the under side of the pipe and 70 a few perforations i are formed in the upper side or wall of the pipe. These perforations serve to admit air into the helmet, the air being supplied with a force sufficient to prevent gases or dust from entering from 75 the bottom of the helmet and to supply fresh air to the wearer. The pipe G extends from the helmet to a belt H on the waist of the person wearing the helmet and is there connected to a valve or cut off cock I 80 to which is connected one end of a flexible hose pipe J which leads to a source of compressed air supply. The location of the source of air supply depends on the kind of work the user of the helmet is employed on. 85 Thus, if it is being used by a fireman he may carry a tank of compressed air suspended or attached to his shoulder or back; if it is being used by a miner, or by one engaged in coating the interior of brewers' casks, the 90 hose may lead to a stationary compressed air tank or reservoir.

Around the bottom of the shell a cape L is secured in any manner, from one edge of the doorway to the other, and is attached to the door by hooks m, so that it swings open when the latter is opened. The cape L assists in excluding gases, smoke, etc., and the impure air escapes from the helmet under the cape. An outside cape M is se- 105 110

cured to the flange *n* of the shell to cover the shoulders of the wearer as shown in Fig. 1 in dotted lines.

In order to protect the neck of the wearer from the entering currents of air, a collar extending up to the ears and around the neck under the chin should be worn, and any suitable collar may be employed for the purpose as it forms no part of the present invention.

Having thus described my invention what I claim is:

A helmet constructed to envelop the head and provided at its lower end with an open-

ing and having a laterally extending flange 15 surrounding such opening, a cape attached to the inner side of the helmet in line with the opening and adapted to encircle the neck of the wearer and a second cape secured to the lower portion of the helmet by means of 20 the exterior flange thereof and adapted to envelop the shoulders of the wearer.

In testimony whereof, I affix my signature, in the presence of two witnesses.

GEORGE B. SPARKS.

Witnesses:

GEORGE BAILEY,
HOWARD MOORE.
